NECKTIE AND HOLDER THEREFOR

Filed Feb. 18, 1946

UNITED STATES PATENT OFFICE

2,504,887

NECKTIE AND HOLDER THEREFOR

Eben L. Scott, Mission, Kans.

Application February 18, 1946, Serial No. 648,257

3 Claims. (Cl. 2—152)

1

This invention relates to neckties and holders therefor and has for a principal object to provide a latch-like connection between the tie and holder to facilitate removal and attachment of the tie and which is adapted for automatic release from the holder in case the tie is caught in a machine or the like.

Other objects of the invention are to provide a holder including a latch element formed of wire and adapted to frictionally engage in a socket element about which the simulation of a knot is formed; to provide a latch element and holder of simple and inexpensive construction and which when applied to a collar supports a preformed tie in natural position.

In accomplishing these and other objects of the invention hereinafter pointed out, I have provided an improved structure, the preferred form of which is illustrated in the accompanying drawing wherein:

Fig. 1 is a perspective view of the front portion of a collar to which is attached a necktie and holder embodying the features of the present invention.

Fig. 2 is a top plan view of the holder and tie as it appears when removed from the collar.

Fig. 3 is a perspective view of the holder and tie in spaced relation and showing the latch element carried by the tie.

Fig. 4 is a side elevational view of the tie particularly illustrating the latch element.

Fig. 5 is a perspective view of the latch element and the member on which the knot of the necktie is formed.

Referring more in detail to the drawings:

1 designates a holder, 2 a necktie and 3 a latch element embodying the features of the present invention. The holder 1 includes a formed strip of resilient material curved retractively from the center 4 toward the ends 5 and 6 to somewhat conform with the neck of the wearer and shaped to provide slightly upwardly extending wings 7 and 8 to fit between the neck band and reverse or outer fold 9 of a collar 10, the upper edge 11 of the holder closely engaging the folded edge 9 of the collar and the lower edge 12 being positioned substantially along the attachment point of the neckband with the body of the shirt or other garment bearing the collar.

Formed intermediate the ends of the strip is an opening 13 intersected by a slot 14 extending from the lower edge 12 and having side edges 15 and 16 converging toward the opening 13 to provide an entrance space for passing the threads for attaching the button 17 of the collar when the holder is to be attached thereto with the

holder engaging under the button and the attaching threads within the opening 13. When thus engaged, the holder is securely anchored to the collar and provides a substantially secure support for the necktie element 2, later described. To further secure the holder and to better retain the wings 13 and 19 of the collar, the holder is provided with finger-like clamps 20 and 21 having ends 22 suitably attached to the holder by soldering or the like if the holder is formed of metal or in the case of plastic by cementing or bedding the anchoring end of the clamp within the material of which the holder is formed. The opposite ends of the clamps curve inwardly toward the front wings of the collar to press the wings of the collar against the holder as shown in Fig. 1.

Formed on the holder preferably in parallel alignment with the edges 15 and 16 of the slot 14 are loop-like members 23 and 24 attached to the holder similar to the clamps and forming facing slot-like openings 25 for engagement with the latch element 3. The necktie 2 includes a knot portion 26 simulating the knot of a four-in-hand tie which is shaped about a form member 27. The member 27 may be constructed of plastic or other material to provide front and rear walls 28 and 29 spaced apart by sides 30 and 31, and a top 32 to form a recess 33 opening through the lower edge of the form as indicated at 34. The sides of the form preferably converge inwardly toward the opening 34 to somewhat conform with the shape of the knot 26 and to provide upwardly and laterally diverging portions on the interior of the recess to frictionally engage a part of the latch element 3.

The latch element 3 is preferably formed of resilient material such as spring wire and is formed of a length of wire bent intermediate its ends to provide a bar portion 35 having downwardly and outwardly converging portions 36 and 37 and inwardly and downwardly converging portions 38 and 39, which latter portions somewhat conform with the side edges of the recess so that they frictionally engage therein and anchor the latch member to the necktie. The portions 38 and 39 may be formed in sinuous curves so as to promote contact with the form element 27 and they terminate in laterally extending parallel portions 40 and 41 carrying upwardly and outwardly diverging latch finger portions 42 and 43, the terminals of which are bent outwardly and then downwardly to form substantially triangular shaped latch portions 44 and 45 to engage in the slot-like openings 25 of the keeper lugs 23 and 24 on the holder. The in-

wardly and downwardly sloping terminals are adapted to slide on the keeper lugs 23 and 24 at the lower ends of the slots 25 so that should the tie be caught in a machine or the like, the fingers 42 and 43 will be moved toward each other to release the latch element 3 from the holder 1, thereby providing for safety of the workman of a machine or other device in which the tie may be caught.

In applying the invention constructed as described, the holder element 1 is slipped between the collar folds 18 and 19 and engaged over the collar button 17 as shown in Fig. 1. The portions 36 and 37 of the latch element 3 are moved into the opening 34 of the form 27 which is contained within the knot 26 of the tie 2. Upward thrust of the latch element causes the diverging portions 38 and 39 to spring together as they pass through the opening 34, after which they spring apart to engage the sides of the recess 33 of the form member. When the latch element is applied to the tie, the finger portions 42 and 43 thereof project upwardly in diverging relation with the rear of the knot 26 as shown in Fig. 4. The fingers may then be grasped between the finger and the thumb of a person to press the terminal ends thereof together and permit passage thereof between the keeper lugs 23 and 24 on the holder. When pressure is relieved the triangular-shaped terminals 44 and 45 snap into the slot-like openings 25 to secure the tie to the holder 1. The upper side edges of the knot are then tucked under the collar wings 18 and 19, after which the collar wings are drawn under the clamp fingers 20 and 21 as shown in Fig. 1. The tie is readily removed from the holder by applying the thumb and finger around the knot to press the spring fingers 42 and 43 of the latch element together, thereby withdrawing the triangular-shaped terminals 44 and 45 from the keeper lugs 23 and 24 of the holder. The tie is then free and may be withdrawn from the collar.

The holder is removed from the collar by sliding it off of the collar button 17 of the shirt. When it is desired to wear a different tie, the tongue of the latch element provided by the portions, 35, 36—37 and 38—39 may be withdrawn from the recess 33 of the form and re-inserted in the form member of another tie to be used which may then be applied to the holder after the holder is attached to the collar.

While I have particularly illustrated and described a necktie simulating a four-in-hand tie, it is obvious that the invention may be carried out in the connection with a bow or other form of tie without departing from the spirit of the invention.

From the foregoing it is obvious that I have provided a necktie holder and tie adapted to be removably secured to the holder by a resilient latch member which is readily withdrawn in case the tie should become caught or placed under excessive strains but which is otherwise

secured in proper position when worn. It is also obvious that the latch may be readily manipulated and removed from one tie and applied to another tie when it is desired to change ties.

5 It is also obvious that the invention as above described provides a tie which is readily applied by a child or person unable to form complicated knots.

What I claim and desire to secure by Letters 10 Patent is:

1. In a device of the character described, a necktie holder adapted for insertion under the fold of a collar and having laterally spaced latch engaging portions thereon, latch means separate 15 from the holder and including a wire-like member providing a tongue and laterally spaced resilient latch fingers for engaging the latch engaging portions of the holder, a necktie having a socket for receiving the tongue, and clamps on the holder for engaging wings of said collar.

2. In a device of the character described, a necktie holder comprising an arcuate strip of sheet material adapted for insertion under a fold of a collar and having an opening adapted 25 for engaging the attaching means for a button of a collar to anchor said holder and having a notch intersecting said opening adapted to pass said attaching means into the opening, keeper lugs projecting from the convex side of the holder 30 at the respective sides of the slot, and a separate latch member having a portion adapted for connection with a necktie and having laterally spaced resilient latch fingers engageable with the keeper lugs of the holder.

3. In a device of the character described, a necktie holder comprising an arcuate strip of sheet material adapted for insertion under the fold of a collar and having a button engaging opening, loop members projecting from the convex side of the holder on the respective sides of the button engaging opening, and a separate latch member formed of wirelike material and having a tongue provided with laterally extending corrugations adapted to engage in a socket 40 of a necktie and terminating in laterally diverging resilient fingers provided with angularly shaped terminals for engaging in said loops.
